UNITED STATES PATENT OFFICE.

CAROLINE L. LEWIS AND CHARLES E. MIXER, OF BOSTON, MASSACHUSETTS.

DESIGN FOR A CLASP MEMBER.

SPECIFICATION forming part of Design No. 30,948, dated June 6, 1899.

Application filed April 26, 1899. Serial No. 714,504. Term of patent 14 years.

To all whom it may concern:

Be it known that we, CAROLINE L. LEWIS and CHARLES E. MIXER, of Boston, in the county of Suffolk and State of Massachusetts, 5 have invented a certain new and original Design for a Clasp Member, of which the following is a specification.

This invention relates to a design for the members of fasteners or clasps; and the essential feature of the design consists in the novel shape and configuration hereinafter fully described and claimed, and clearly illustrated upon the drawings.

Figure 1 represents a longitudinal section 15 through the member of a clasp or fastener embodying our design. Fig. 2 represents a plan view of the same.

Referring to the drawings, *a* indicates the lower part or limb, and *b* the upper part or 20 limb thereof. The two parts or limbs are

joined by a tubular end portion *c* and lie substantially parallel. The upper limb at *b'* is inclined outwardly from the limb *a* and has an end *b²*, which lies in a plane intersecting the limb *a*, the space between the portion *b²b'* 25 and the limb *a* being triangular.

In general appearance the clasp member resembles a triangle and a circle joined by a bridge.

We claim—

The design for a clasp member substantially as shown and described.

In testimony whereof we have affixed our signatures in presence of two witnesses.

CAROLINE L. LEWIS.
CHARLES E. MIXER.
